UNITED STATES PATENT OFFICE.

RICHARD WALther AND HUGO WALther, OF WERDAU, SAXONY,
GERMANY.

ELECTRIC-ARC LAMP.

SPECIFICATION forming part of Letters Patent No. 338,122, dated March 16, 1886.

Application filed July 15, 1885. Serial No. 171,669. (No model.)

To all whom it may concern:

Be it known that we, RICHARD WALther and HUGO WALther, of Werdau, Saxony, Germany, have invented a new and Improved 5 Electric-Arc Lamp, of which the following specification is a full, clear, and exact description.

This invention relates to an electric-arc lamp; and has for its object to obtain a steady 10 light, the regulation of the arc being produced directly by the current itself. The current influences one or two solenoidal cores in such a way that they are attracted to a greater or less degree, and are thus drawn into or out 15 of the solenoidal coil. This motion is transmitted to lever mechanism that lifts or lowers the carbon-holder, as will be hereinafter described.

In the accompanying drawings, Figure I is 20 a face view of our improved lamp. Fig. II is a side view of the same. Fig. III is a top view, and Fig. IV a horizontal section on line $x y$, Fig. I. Figs. V to VIII are detail views of various parts thereof.

In the drawings the letter E represents a magnetic brake that prevents the cores $a b$ of the solenoid from dropping out of their coils 25 A B too readily. This brake is composed of the shoes $e f$, Figs. II and III, which are placed 30 at a proper distance from the cores $a b$, so as to effect the magnetic braking of the latter. The shoes are provided with adjusting mechanism, (see Fig. I,) by means of which they may be placed nearer to or farther away from 35 the cores, and thus the brake may be made to act with greater or less power. The current branches off at c , passes through the solenoid A B, reunites at d , and is conducted to the upper carbon by means of its tube C. Thence 40 it passes to the lower carbon, and leaves the lamp at g . The current causes the regulation of the arc by attraction of the cores, and a consequent movement of rod h in conjunction

with the brake, which acts by reason of the attraction of the cores $a b$ upon the shoes $e f$. 45 When the lamp is ignited, the carbons are placed with their ends upon each other. The current draws the cores into the coils, and thus the tube or holder of the upper carbon is raised by means of rod h and tongue i of a lever, k , so that the carbon points are placed at a normal distance from one another. When the carbons are consumed, the current is decreased, and the cores $a b$ will drop. The tongue i liberates the tube C so that the latter 50 may descend. This lowering of tube C takes place without any irregularity and almost imperceptibly, as the current by increasing in strength immediately produces an equalization upon cores $a b$, brake E, rod h , and levers $i k$. 55 The cores move freely within the coils and their descent is produced by the brake in such a way that the attraction of the cores by the current is in proper relation to the normal force of the current. In this way the current 60 regulates the arc promptly without the use of branching conductors.

The lamp may be fitted for various purposes, and may have a stationary or an adjustable illuminating-point.

We claim as our invention—

The combination of an electric-arc lamp having solenoids A B and cores $a b$ with rod h , lever k , tongue i , and with the magnetic brake-shoes $e f$, adapted to be placed nearer 75 to or farther away from the cores $a b$, substantially as specified.

In testimony whereof we have signed our names to this specification in the presence of two subscribing witnesses.

RICHARD WALther.
HUGO WALther.
